GUTTER SUPPORT

Max Rachlin, Flushing, N. Y.

Application November 20, 1940, Serial No. 366,477

9 Claims. (Cl. 248—48.2)

This invention relating as indicated to an eaves trough support, is more particularly directed to an article of manufacture, in which an attaching plate has permanently connected thereto a gutter supporting circle. The attaching plate is adapted to lie flush against any vertical surface, such as a facia board or the outer vertical surface of a roof rafter, and is provided with apertures through which attaching means such as nails, screws, or the like, may extend. The gutter circle is rigidly secured to the attaching plate and is seated in slots in the attaching plate in such manner that side-wise or lateral movement is prevented and also in such manner that downward movement of the circle, even under a heavy load, is prevented, due to a novel arrangement of securing and seating the circle with respect to the plate.

It is one object of my invention to provide a gutter support which is useful in replacement jobs because my support can be affixed to the facia board or the end of a roof rafter without the necessity of removing any of the roofing material. This type of hanger is not new but heretofore the bracket type of hanger has been too expensive or too weak.

For example, one type of bracket hanger comprises a channel shaped member, in cross section, that is the facia board abutting portion as well as the circle itself is channel shaped. This is a sheet metal stamping but is objectionable from the standpoint of cost since considerable metal is used and this type of hanger lacks the necessary strength.

Other types of bracket hangers are too expensive because of the number of operations required in their manufacture and the amount of metal required.

It is an object of the invention to improve all known types by providing an interlock between the circle and the plate and riveting the plate to the circle. In this way the rivet does not carry all of the weight, which lessens the shearing force, and the circle cannot turn about the rivet as an axis, which would cause failure under load.

It is a further object of the invention to provide a hanger in which the plate is rigidly connected to the circle by some such means as a rivet and thus avoid bolted connections, since it has been found that bolted connections loosen due to vibration.

A further object of the invention is to eliminate one operation of the roofer where shanks and circles are used. My combined plate and circle is manufactured under the conditions of mass

production and a stronger support can be obtained at less cost under close supervision. Heretofore, where shanks and circles are used, the circle is bolted to the shank by a roofer who is standing upon a ladder, usually at a high elevation, and under conditions where it is difficult to work.

It is a still further object of the invention to provide an eaves trough support in which the gutter circle is held rigidly at right angles to the facia board, and one in which the circle will remain at right angles.

It is another object of the invention to provide a less expensive eaves trough support and yet one which possesses more strength than the prior bracket types of support or the shank and circle type.

To the accomplishment of the foregoing and related ends, said invention, then, consists of the means hereinafter fully described and particularly pointed out in the claims.

The annexed drawings and the following description set forth in detail certain structure embodying the invention, such disclosed means constituting, however, but one of various mechanical forms in which the principle of the invention may be used.

In said annexed drawings:

Figure 1 is a side elevation with the gutter in section.

Figure 2 is a front elevation with parts broken away.

Figure 3 is vertical section through the plate.

Figure 4 is a horizontal section on line 4—4 of Figure 2.

Figure 5 is partial elevation of the gutter circle.

Figure 6 is a front elevation of a modified form of the attaching plate.

Figure 7 is a central vertical section of Figure 6.

Figure 8 is a front elevation of another modification of the attaching plate.

Figure 9 is a central vertical section of Figure 8.

Figure 10 is a front elevation of a still further modified form of the attaching plate and

Figure 11 is a central vertical section of Figure 10.

Referring now to the drawings and more particularly to Figure 1, it will be seen that my eaves trough support comprises a gutter circle 1 and an attaching plate 2, the circle having an outer hook 3, adapted to receive a retaining clip 4. The circle also has another hook portion 5,

adapted to retain the inner edge of the gutter 20, that lies opposite to the bead portion.

The circle 1 has its rear upper vertical edge notched so as to provide a tongue like portion 6 (see Figs. 3 and 5) which is adapted to fit snugly into the slot 8, located adjacent to the upper edge of the plate 2 and centrally thereof. The plate 2 is additionally provided with another and larger slot A, in which the circle 1 is snugly seated so that the lower curved surface 10 thereof, rests on the seat 12 in plate 2.

Particular attention is directed to the interlock shown in Figures 3 and 5. The circle 1 has a rearwardly projecting portion 6 which forms an upper shoulder 25 and a lower shoulder 24. The shoulder 25 is adapted to abut the surface 22 in slot 8 (see Fig. 3) and similarly, the shoulder 24 is adapted to abut the surface 20 in such slot. An additional anchor means is provided in the form of a shoulder 29 in the circle 1, which abuts surface 27 in the attaching plate 2. By these means, movement about rivet 13 as an axis, is definitely precluded. Furthermore, a considerable share of the weight borne by the gutter is transmitted to the surface 20 on plate 2, since shoulder 24 on the circle directly abuts this surface. As a consequence of this construction, the shearing stress upon rivet 13 is greatly reduced. The surfaces 22, 20, 27 and 12 all coact to prevent clockwise or counter-clockwise movement of the circle about the rivet 13 as an axis and thus reduce the strain on rivet 13. The movement of the circle 1 inwardly with respect to the attaching plate 2, is positively prevented because the seat 12 in the protuberance 11 maintains the circle in a predetermined position and the protuberance 11 being slotted prevents lateral movement of the circle 1 since it outwardly embraces the lateral faces of the circle. The surfaces 21 and 21' of the slot A directly abut the lateral or flat surfaces of the gutter circle 1, thus preventing twisting or turning of the circle.

The plate 2 has struck up therefrom a lug 14, this lug extending at right angles to the plate and being provided with an aperture 9. The circle 1 is also provided with a corresponding aperture and a rivet 13 extends through both such apertures, thus rigidly and permanently securing the circle to the plate.

Further means of maintaining the circle 1 in fixed relationship is provided, this taking the form of a slot A in the substantially hemispherical protuberance 11. This slot is bounded on three sides by the vertical walls 21 and 21' and transverse seat 12. It is to be particularly noticed that the slot A does not extend throughout the full 180 degrees of the protuberance 11. It is also to be noted that the plate itself, is provided with a slot that is continuous with the slot 21 and in which the vertical upper rear portion 7 (see Fig. 3) of the circle 1 is received. This slot in the plate itself, or stated in other words, in the flat portion of the plate, communicates from the opening formed by striking up lug 14, with the slot A.

The rivet 13, or other equivalent securing means, anchors the circle at one point with respect to the plate and the circle bears downwardly against the seat 12, the seat preventing further downward movement. Any lateral movement is prevented in one instance by the integral lug 14 and also by the walls 21 and 21' of the slot A in the protuberance 11. Further anchorage is obtained by means of the projecting portion 6 fitting snugly in the slot 8,

and by engagement of surfaces 25, 24 and 29 on the circle, with surfaces 22, 20 and 27 respectively, on the plate.

It is to be observed that the rear surface of the plate 2 coincides with the rear edge of the circle 1 as shown in Figure 3, so that a portion of the load which the gutter may receive, is transmitted directly to the facia board 19. A further advantage of this construction is that the gutter is drawn inwardly so as to lie well under the eaves. In the past, difficulty has occurred with bracket type hangers because the gutter was held outwardly, to such an extent that water would flood between the gutter and the house, thus rotting the facia board and marring the walls of the house.

Referring now to Figure 6, it will be seen that I have provided a modification which is somewhat cheaper than the preferred embodiment although not as strong. In this case, the attaching plate 2' is substantially flat except for the upstanding lugs 14' and 30. The circle 1 is adapted to be secured to the lugs 14' and 30 by means of rivets or, if desired, by welding. Rivets are adapted to extend through the apertures 8' and 31, thus maintaining the circle 1 in a firm position and in such manner that twisting of the circle with respect to the plate is eliminated. The plate 2' is additionally provided with a slot 8' similar to the slot 8 in the plate 2. This slot performs the same function as slot 8 and need not be described in detail. Suffice it to say that the projection 6 extends into the slot 8' and the surfaces 25, 24 and 29 on the circle respectively engage the surfaces 22', 20 and 27' on the plate 2'. In each of the modifications embodied in Figures 6 to 11 inclusive, the circle has not been shown since the parts of the plate can be seen more clearly. It will, of course, be understood that the circle is adapted to fit into the plate in the same manner as is described in connection with the preceding figures.

Referring to Figure 8, there will be found another modification which is believed to be somewhat stronger than the embodiment shown in Figures 6 and 7. In this case, the plate 2a has a slot 8a and an upstanding lug 14a, both of which perform the same functions as described in connection with slot 8 and lug 14 of Figures 2 and 3. This modification differs from the preceding forms of the invention in that the protuberance 34 is formed by striking out a central lower portion of the plate 2a. It will be seen that the protuberance has parallel substantially triangular walls 36 and 37 which are joined by a transverse wall 34. The upper edge 33 of the transverse wall forms a seat comparable to seat 12 of Figure 2. This form of the invention gives exceedingly strong support to the gutter circle inasmuch as the transverse wall 34 is an integral part of the plate 2a. It is believed that the circle itself, will fail before failure of the seat 33 due to any downward thrust. The upper edge of the circle 1 is interlocked to the plate in the same manner as previously described since the projection 6 on the circle fits snugly into the slot 8a in the plate 2a.

Referring now to Figure 10, a still further modified form is shown which differs somewhat from the preceding forms in the particular shape of the protuberance. This modification has an upstanding lug 14b and a slot 8b, which function in the same manner as lug 14 and slot 8. The lower central portion of the plate 2b has a

part thereof, struck up and then bent upon itself as most clearly shown in Figure 11. The protuberance 40 having the slot C, is provided with a seat 41 against which the lower edge 10 of the circle is designed to abut. In this form, the slot C, similar to the slot A prevents any lateral movement of the gutter circle 1.

In all forms, the various plates are provided with apertures adapted to receive fastening means such as nails or screws.

It is to be understood that the precise outline of the plates 2, 2', 2a and 2b may be varied from those shown. In some instances, it may be less expensive to form the vertical side edges of the plates at right angles to upper horizontal edge. It may also be desired to form the lower horizontal edge in a straight line parallel to the upper horizontal edge. It is further to be understood that the lug 30 and the various protuberances 11, 34 and 40 may extend outwardly any distance depending upon the size of circle employed with the attaching plate.

It is to be understood that the eaves trough support of my invention may be attached to a facia board 19, or, where the eaves project and the rafters are exposed, plate 2 may be attached to the outer vertical end of a roof rafter, or any other supporting surface.

In the foregoing description, it will be seen that I have provided an eaves trough support which is an improvement over prior bracket types of gutter hangers and one which can be installed after the roof is applied. It will also be noticed that the plate and circle being in one piece, eliminates an awkward operation by the roofer where shanks and circles have been used. It will be seen that my eaves trough support is inexpensively manufactured, thus providing a support which is stronger at less cost. It will further be noted that the employment of my eaves trough support permits adjustment of the gutter to any degree, with great facility, and that the gutter circle is rigidly held at right angles to the facia board.

Finally it will be noted that any load bearing downwardly is effectively taken care of by the seat 12 in the protuberance 11 plus several interlocks between surfaces in the upper portion of the gutter circle with surfaces in the upper portion of the attaching plate.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. An article of the character described comprising a plate and a gutter circle, said circle being secured to a portion of said plate, said plate being provided with a protuberance, said protuberance having a slot therein and said circle fitting into said slot.

2. An article of the character described comprising a plate and a gutter circle, said circle being secured to a portion of said plate, said plate being provided with an outstanding protuberance, said protuberance and plate having a slot therein and said circle fitting into said slot.

3. An article of the character described comprising a plate and a gutter circle, said circle being secured to a portion of said plate, said plate being provided with an outstanding protuberance, said protuberance having a slot therein and said circle fitting into said slot, said plate also having a slot therein, such slot being spaced from said protuberance, and said circle having a tongue like portion snugly fitting into such last named slot, whereby said circle is interlocked with said plate.

4. An article of the character described comprising a plate and a gutter circle, said circle being secured to a portion of said plate, said plate being provided with an outstanding protuberance, said protuberance having a slot therein and said circle fitting into said slot, said plate also having a slot therein, such slot being spaced from said protuberance, and said circle having a tongue like portion snugly fitting into such last named slot, said plate having another slot therein, said last named slot being a continuation of the slot in said protuberance and said circle having a portion seated in such continuous slot.

5. An article of the character described comprising a plate and a gutter circle, said circle being secured to a portion of said plate, said plate being provided with an outstanding protuberance, said protuberance and plate having a slot therein and said circle fitting into said slot, said protuberance being substantially hemispherical and the slot therein extending less than 180 degrees.

6. An article of the character described comprising a plate and a circle, said plate having a slot therein and said circle having a portion thereof seated in said slot, said slot having parallel lateral walls joined by a transverse surface, the lower edge of said circle being seated upon said transverse surface.

7. An article of the character described comprising a substantially flat plate and a gutter circle, said plate having an upstanding lug to which said circle is secured, said plate having a protuberance in the form of a bent strip, a vertical slot in said bent strip and a lower portion of said circle being received in said slot.

8. An article of the character described comprising a plate and a gutter circle, said plate having an upstanding lug to which said circle is secured, said plate having an outstanding, load bearing protuberance, said protuberance projecting out of the interior body portion of said plate and lying below said lug, said protuberance having a bearing surface extending transversely with respect to said circle, the lower edge of said circle being seated upon said bearing surface.

9. An article of the character described comprising a substantially flat plate and a gutter circle, said plate having an upstanding lug to which said circle is secured, said plate having an outstanding protuberance, said protuberance projecting out of the interior body portion of said plate and lying below said lug, said protuberance having a bearing surface therein, said circle being substantially flat and extending in a plane at right angles to the plane of said flat plate, the lower edge of said circle being seated upon said bearing surface.
